UNITED STATES PATENT OFFICE.

JOHN S. ROBBINS, OF SAN FRANCISCO, CALIFORNIA.

SHIP'S RUDDER.

Specification of Letters Patent No. 13,601, dated September 25, 1855.

To all whom it may concern:

Be it known that I, JOHN S. ROBBINS, of the city of San Francisco, in the county of San Francisco and State of California, have 5 invented a new and useful Improvement in Rudders for Ships and other Vessels; and I do hereby declare that the following is a full, clear, and exact description of the same, reference being had to the accompanying drawings, forming part of this specification, in which—

Figure 1, is a side view of my invention, and Fig. 2, a sectional plan of the same.

Similar letters of reference indicate corresponding parts in both figures.

This invention consists in a certain method of applying and combining two rudders to act simultaneously whereby the pressure—caused by the resistance of the 20 water as the vessel passes through it—upon one rudder, while the vessel is in motion, is balanced by the pressure upon the other, thus the steersman is enabled to hold the helm in any position without difficulty. 25 The invention also tends to diminish the leeway of the vessel and brings the vessel around within a less distance.

To enable those skilled in the art to make and use my invention I will proceed to 30 describe its construction and operation.

A, is a rudder hung from the stern post B, of a vessel in a similar manner to the rudder commonly employed but having little more than half the area. This rudder 35 may be operated by a tiller, or steering wheel of the common kind, or any steering apparatus applicable to the common rudder. C, is another rudder not quite so wide as the rudder A, hung on an upright post or 40 shaft *a*, the lower end of which is supported by the keel E, of the vessel which is extended beyond the stern post for the purpose, and the upper end by a stay F, standing out from the stern of the vessel, or the 45 upper end might be framed into or secured to the upper part of the stern of the vessel if the stern post B, stood far enough under. The rudder C, is hung to swing between the shaft *a*, and the rudder A, with

50 just room to clear the rudder A. The rudder A, has rigidly connected with it two strong iron arms *b*, *b*, one standing out on each side. These arms are suitably stayed to give them great stability. The rudder

C, carries two arms *b'*, *b'*, similar to *b*, *b*, 55 and these arms *b'*, *b'*, are connected by two connecting rods *c*, *c*, of equal length to the arms *b*, *b*. The points of connection of the rods to the arms *b*, *b*, and *b'*, *b'*, must all be equidistant from the centers of motion 60 of their respective rudders and lines drawn from the several points of connection through the centers of motion must all form corresponding angles with the sides of the respective rudders, by which arrangement 65 the connecting rods are caused to be at all times parallel with each other and with the rudders, the rudders being also parallel with each other when not amid-ships, and in line with each other when amidships. 70 As the rudders depart from the midship position one swings to one side and the other to the other side, but as both are parallel they both tend to give the vessel the same direction, and both being of equal 75 area the resistance which they meet with as the vessel passes through the water is equal. This resistance acts upon one to force it into a midship position and on the other to force it farther from such a position, but as their connection does not allow either to approach or depart from the midship position without the other, the effect of the resistance is to hold them permanently in any position they may occupy the 80 same as if they were locked. This relieves the helmsman not only while the helm is kept stationary but in moving it as it is mainly the resistance caused by the motion of the vessel which makes it require so 85 much power to move it.

I have described the rudders A, and C, as being of slightly unequal size A, being a little the widest, this is necessary to a perfect balance as the water coming off the 90 stern of the vessel will not act quite so effectively on A, as it would upon C, which is fully exposed.

What I claim as my invention and desire to secure by Letters Patent, is—

Arranging the two rudders and combining them by means of arms *b*, *b*, and *b'*, *b'*, and connecting rods *c*, *c*, substantially as and for the purpose herein set forth.

JOHN S. ROBBINS.
